UNITED STATES PATENT OFFICE.

EDWARD KIRBY BOTTLE, OF NIAGARA FALLS, NEW YORK, ASSIGNOR TO
THE CARTER & COMPANY, LIMITED, OF SAME PLACE.

MANIFOLD MEMORANDUM-BOOK.

SPECIFICATION forming part of Letters Patent No. 469,930, dated March 1, 1892.

Application filed July 20, 1891. Serial No. 400,076. (No model.)

To all whom it may concern:

Be it known that I, EDWARD KIRBY BOTTLE, of Niagara Falls, in the county of Niagara, in the State of New York, have invented new and useful Improvements in Manifold Memorandum-Books, of which the following, taken in connection with the accompanying drawings, is a full, clear, and exact description.

This invention relates to the class of memorandum-books which are chiefly used by salesmen in mercantile establishments and in which a carbon-sheet or transfer-leaf is adapted to be inserted between two adjacent memorandum-leaves to produce duplicates of the memoranda entered in the book, the memorandum-leaves being detachable and the original memoranda being sent to the desk of the accountant or book-keeper, and the copies or duplicates are given to the purchaser of the goods entered in the memorandum-book.

The object of my present invention is to simplify and facilitate the attachment of the memorandum-leaves to the supporting-back of the book; and to that end it consists, essentially, of a memorandum-book comprising a supporting back plate, a block of memorandum-leaves secured at one end to the end of said back plate, and frictional paper-holders secured to said back plate and engaging opposite edges of the memorandum-leaves.

The invention also consists in certain novel features of the detail construction of the memorandum-book, as hereinafter fully described, and specifically set forth in the claims.

In the annexed drawings, Figure 1 is a perspective view of an open memorandum-book embodying my invention. Fig. 2 is a longitudinal section on line $x-x$, Fig. 1. Figs. 3 and 4 are transverse sections respectively on lines $y-y$ and $z-z$, and Fig. 5 is a detached edge view of the transfer-leaf-holding clamp.

Similar letters of reference indicate corresponding parts.

$c c c$ represent the memorandum-leaves, which are piled in the form of a block and preferably formed of a continuous web of paper folded successively and alternately in opposite directions and perforated along the lines of folding to facilitate the separation of

the leaves when desired. This block of leaves 50 I place upon a stiff back plate P , which I preferably form with an extension P'' to serve as a cover for the book. I do not, however, limit myself to the use of a cover for the book; but the back plate P is essential to my improvements, inasmuch as it affords a firm support for the memorandum-leaves. To the top of the upper end portion of this back plate I attach a metal plate C , which extends across the plate P and terminates with vertically-slotted 55 ears $C' C'$, which project at right angles from the plane of the plate. Said plate C is also formed with a vertical wall C'' , extending across the back plate P for the purpose hereinafter explained.

a denotes a clamp, which is composed of two bars hinged together at one end and having the opposite end of one bar terminating with a tongue passing through the other bar and clinched to lock them together. Between these 60 bars is clamped the carbon-sheet or transfer-leaf d . The ends of the said clamp extend through the slots of the ears $C' C'$, which sustain the clamp at right angles to the side edges of the back plate P and movably toward 65 and from the plane of said plate. The block of memorandum-leaves $c c c c$ is inserted at one end underneath the clamp a , which has attached to it the transfer-leaf d , and thus carries said leaf over the aforesaid block and 70 in a convenient position to allow it to be readily introduced between the two uppermost memorandum-leaves $c c$ when required to produce duplicate memoranda. In introducing the block of memorandum-leaves under the 75 clamp a said block is to be pushed up against the vertical wall C'' of the metal plate C , whereby said block is confined endwise in one direction.

In order to retain the free ends of the memorandum-leaves compactly upon the back plate P while removing the two top leaves from the block, I provide the said back plate with suitable frictional holders engaging the side edges of the memorandum-leaves. For this purpose 90 I prefer to provide the back plate P with side walls $P' P''$ and glue onto the inner sides of 95 said walls strips or small pieces of sand-paper

or cinery-paper *b b*, which by contact of their rough or frictional surfaces with the edges of the memorandum-leaves hold the free ends of said leaves compactly piled on the back plate *P*.

Having described my invention, what I claim as new, and desire to secure by Letters Patent, is—

1. The combination of the back plate *P*, provided with side walls *P' P'*, the block of memorandum-leaves *c c c*, secured to one end of the back plate, with the transfer-leaf on top of the block, and friction-sheets secured to the inner sides of the side walls and engaging the edges of the aforesaid block, as set forth.
2. The combination of the back plate *P*, provided with side walls *P' P'*, friction-sheets *b b* on said walls, the block of memorandum-sheets *c c c*, lying with one end on the end of the back plate, the clamp *a*, lying upon said

end of the block, and the transfer-leaf *d*, attached to said clamp, as described and shown.

3. The improved memorandum-book consisting of the back plate *P*, provided with the side walls *P' P'*, the plate *C*, extending across the upper end of the back plate and secured thereto and formed with vertically-slotted ears *C' C'*, the clamp *a*, having extensions passing through said ears, the block of memorandum-leaves confined between said clamp and underlying plates, the transfer-leaf *d*, secured to the clamp, and the friction-sheets *b b* on the walls *P' P'*, substantially as set forth and shown.

In testimony whereof I have hereunto signed my name this 9th day of July, 1891.

EDWARD KIRBY BOTTLE. [L.S.]
